United States Patent Office.

EDWIN CHARLES RUTHVEN, OF PHILADELPHIA, PENNSYLVANIA.

Design No. 2,833, dated November 19, 1867.

DESIGN FOR ORNAMENTAL TYPE.

The Schedule referred to in these Letters Patent and making part of the same.

TO ALL WHOM IT MAY CONCERN:

Be it known that I, EDWIN CHARLES RUTHVEN, of the city and county of Philadelphia, Pennsylvania, have originated a new Design for Printing-Type, of which the following is a full description, reference being had to the accompanying drawings or specimens, making a part of this specification, in which the entire alphabet, both of capitals and small letters, is shown, the other signs and figures being similar in style, design, and ornamentation to those shown.

What I claim as my production, and desire to secure by Letters Patent, is—

The design for a printing-type as shown and set forth.

E. C. RUTHVEN.
